UNITED STATES PATENT OFFICE.

LEVI STEVENS, OF FITCHBURG, MASSACHUSETTS.

AXLE-BOX FOR RAILROAD-CARS.

Specification of Letters Patent No. 24,245, dated May 31, 1859.

To all whom it may concern:

Be it known that I, LEVI STEVENS, of Fitchburg, in the county of Worcester and State of Massachusetts, have invented a new and Improved Antifriction-Box for the Axles of Railroad-Car Wheels, of which the following is a full, clear, and exact description, reference being had to the accompanying drawings, making part of this specification, in which—

Figure 1 is a view of my improved box. Fig. 2 a longitudinal vertical section through the same. Fig. 3 a view of the shell or backing of harder metal. Fig. 4 a section 15 through the box showing the position which it occupies on the axle.

The boxes which support the journals of rail road car wheels have been made of bronze with a recess formed in them, into which an anti-friction metal has been run; but to this box there exists the objection that the soft metal is liable when heated by the friction of the rapidly revolving axle (as it melts at a low temperature) to be softened 20 and thrown out of the box which contains it. Other boxes have been made entirely of soft metal (or a composition of zinc, copper and tin) which could be produced at a much less cost than the bronze box; but these boxes 25 were found not to be sufficiently strong to resist the strain and concussions to which they were subjected when applied to the axles of rail road cars, as the weight in such cases is all placed upon the center of the box 30 and is not distributed over its whole surface.

My invention consists in forming the lower or bearing surface of the box of a metal possessing the requisite anti-friction properties, and at the same time melting at 35 a high temperature; and the upper part of the box of a metal which shall possess the requisite strength to enable it to sustain the weight imposed upon it, the hard metal being allowed to project down through the 40 anti-friction alloy and rest upon the journal.

That others skilled in the art may understand and use my invention I will proceed to describe the manner in which I have carried out the same.

50 A shell or backing A shown detached in Fig. 3 is cast of bronze (or other suitable metal), it has short studs or projections a

rising from each corner, and two longer pieces b one on each side; also three short studs or blocks c, one in the middle and one 55 at each end of the shell. This shell is placed in a suitable mold and the antifriction metal is cast onto it, forming the box B, to which the shell A firmly adheres. The composition which I employ is eighty parts of zinc 60 to twenty parts of tin; which I have found to answer the desired purpose, this composition forms a superior anti-friction metal which does not melt at so low a temperature as to render it liable to be softened by 65 the heating of the journals of rail road car wheels. These proportions however are not strictly rigid and may be somewhat varied. The studs a, b, c, support the box B at the points where it is liable to the greatest 70 strain or concussion, the piece b steadyng and guiding the vertical motions of the box in its housings; the studs c at the ends of the box in conjunction with the ends of the shell itself, receive the percussions communicated horizontally to the box in the direction of the axis of the journal, and protect the softer metal from being worn by these side concussions.

The box B is cast of such a thickness in 80 the middle that the tops of the studs c are level with the surface on which the journal runs; this allows the box to rest on the journal at these points, so that any heavy percussion or strain which may be applied to 85 the box in a vertical direction at m Fig. 4, and which would tend to crush or split the box B will be resisted by the shell A and transmitted directly to the journal, without causing too great a strain upon the anti-friction metal.

I do not confine myself to the use of the peculiar antifriction alloy which I employ as this may be varied without altering the spirit of my invention, so long as the alloy 95 employed melts at so high a temperature as not to be softened and thrown out by the heat of the revolving axle, neither do I confine myself to the exact number and position of the studs or blocks c, which project 100 from the case through the antifriction metal, but intend to vary the box in this respect as may be required by the different circumstances under which it is employed.
